AUTOMATIC CHECK FOR REFRIGERATING SYSTEMS

Robert H. Guyton, Chicago, Ill., assignor to The Brunswick-Balke-Collender Company, Chicago, Ill., a corporation of Delaware

Application April 18, 1933, Serial No. 666,698

3 Claims. (Cl. 62—3)

This invention relates to an improved automatic check for refrigerating systems and has for one of its principal objects the provision of means to be incorporated into a refrigerating system whereby the flow of refrigerant to the cooling unit or evaporator is automatically shut off in the event of extreme heat conditions or the like occurring at the evaporator, thereby preventing damage to the unit which would otherwise result.

One of the important objects of this invention is to provide, in connection with the usual refrigerating system, means connected to or associated with, the cooling unit and the liquid refrigerant line whereby any application of undesirable excess heat to the cooling unit or expansion part of the system, either accidental or otherwise, will automatically prevent the further flow of liquid refrigerant through the system.

Another important object of the invention is to provide such an automatic shut-off for refrigerating lines which shall be simple in construction, positive in operation, and which will not be at all likely to get out of order, and which, furthermore, will be immediately available for use whenever necessary while at the same time will not interfere in any way with the usual operation of the apparatus.

Other and further important objects of the invention will be apparent from the disclosures in the accompanying drawing and following specification.

The invention, in a preferred form, is illustrated in the drawing and hereinafter more fully described.

In the drawing—

The figure is a general view, partly diagrammatic, and with most of the important parts shown in section, illustrating the construction and operation of the ordinary type of refrigerating apparatus and with the improved check valve of this invention applied thereto.

As shown in the drawing—

The reference numeral 10 indicates generally the usual compressor of a refrigerating system, the same being operated by means of a motor or the like 12 which is provided with a set of fan blades or similar equipment 14.

In actual practice the fan blades blow a current of air upon a condenser or the like 16 through which the pressure line 18 of the refrigerating system passes, the same being connected to the compressor in the ordinary manner. The pressure line empties into a liquid refrigerant chamber 20 in which is a normal supply of liquid re-

frigerant 22, the same being forced outwardly through a refrigerant supply pipe or the like 24 into a cooling unit or evaporator 26, which in this particular adaptation of the invention includes a control float 28 for maintaining the supply of liquid refrigerant 22 at a desired level. Located in this liquid refrigerant 22 is a set of coils 30 through which the material to be cooled is circulated, which, in this particular embodiment of the invention, is beer, which is originally contained in a keg, barrel, or the like, 32. The beer is forced upwardly into the cooling coils 30 through a pipe 34, being expelled therethrough by compressed air or the like supplied to the barrel through the usual inlet pressure pipe 36. 16 The beer or other liquid enters the cooling unit through an inlet port 38. An outlet port 40 is provided from whence the beer is delivered direct to dispensing faucets or the like.

A return pipe 42 for vaporized refrigerant is 20 provided, which leads through a pressure regulating valve 44 back to the pump 10 by means of a pipe 46. The valve 44 is adapted to control the pressure in the system and acts as a throttling valve.

In installations of this sort it often happens that, in cleaning the same, through accident or otherwise, a quantity of hot, scalding water or steam is introduced into the cooling coils 30 from the beer pipe 34 and this obviously will raise the 30 temperature of the refrigerant 22 to a very undesirable degree and might result in considerable damage to the apparatus.

Accordingly, in order to prevent further inflow of liquid refrigerant, in the event of such undesirable heating, a thermostatic element 48 is placed in or on the beer line 34, which element is connected by means of a tube or the like 50 to a check valve casing 52 in which is mounted a valve element 54, which valve element in turn 40 is adapted to shut off the flow of liquid refrigerant through the pipe 24. The valve 54 is operated by means of the usual power element 56, which comprises a bellows and spring, as illustrated.

This particular apparatus is shown in connection with the serving of beer or other liquid refreshments and includes an auxiliary cooling unit 64 which can be used for cooling bottled beer or the like and which is fed by pipes 66 leading from 50 the main refrigerant pipes 24 and 46. A similar automatic check equipment may be installed in connection with this auxiliary cooling unit if desired or found necessary or advisable.

It will be evident that herein is provided an 55

automatic shut-off means for positively stopping the flow of liquid refrigerant to a system of this type in the event of undesirable or accidental heat conditions, whereby consequent possibility of damage to the equipment is automatically eliminated and which accordingly will be of considerable advantage when installed in equipment of this type, particularly as any written instructions which might ordinarily be furnished to provide against such undesirable conditions are usually not read; or if oral, are quickly forgotten.

10 I am aware that many changes may be made and numerous details of construction varied throughout a wide range without departing from the principles of this invention, and I therefore do not purpose limiting the patent granted thereon otherwise than as necessitated by the prior art.

15 20 I claim as my invention—

1. In a refrigerating system for liquids, having coils for the liquid, said coils immersed in the refrigerant, automatic means for stopping the flow of liquid refrigerant to the coils upon application of excess heat to the same, said automatic means including a power operated valve and a thermostatic element connected to the

power valve, said thermostatic element mounted on the equipment at a point where any such excess heat would be initiated.

2. In a refrigerating system for liquids, having an evaporator, coils for the liquid to be cooled mounted in the evaporator, automatic means for stopping the flow of liquid refrigerant to the evaporator upon application of excess heat to the same, said automatic means including a power operated valve and a connection between 10 the power valve and the liquid circulating system for operating the power valve in the event of undue heat in the system.

3. In a cooling system for liquids, a cooling unit comprising a casing for refrigerant to be 15 evaporated and a coil therein for the liquid to be cooled, automatic means for stopping the flow of liquid refrigerant to the cooling unit upon application of excess heat to the unit, said automatic means including a power operated valve 20 and a connection between the power valve and the liquid supply line for operating the power valve in the event of excess heat in the line, said connection comprising a thermostatic element on the liquid line and a pipe leading from the 25 power valve to the element.

ROBERT H. GUYTON.
